UNITED STATES PATENT OFFICE

ERNEST POCKRANDT, OF MINDEN, NEBRASKA

INCUBATOR TRAY

Application filed May 2, 1929. Serial No. 359,875.

This invention relates to egg trays, and more in particular to egg trays of the type used in incubators, and has as its primary object the provision of a tray of the character set forth, whereby the eggs within the tray may be automatically turned, while the egg laden tray is positioned within the incubator.

A very important object of the invention is to provide a structure of this nature which consists of but few parts, is simple in construction, can be readily and easily assembled for disposition within the incubator, is inexpensive, and thoroughly reliable and efficient in use.

Other objects and advantages of the invention will become apparent during a study of the following description taken in connection with the accompanying drawings, wherein:

20 Figure 1 is a top plan view of my improved egg tray, and showing the tray with the egg positioning frame structure removed.

Figure 2 is a longitudinal sectional view taken through the assembled device.

25 Figure 3 is a top plan view of an egg positioning frame structure or grid.

Figure 4 is a fragmentary detail view of the operating mechanism.

With reference more in detail to the drawings it will be seen that my improved tray, in its contemplated embodiment, comprises an elongated rectangular frame designated generally by the reference character 5. Said frame comprises side members 6-6 and end members 7-7. A plurality of rollers 8 have their opposite ends journaled in the side members 6-6 of the frame as shown in Figure 1, so that the said rollers extend transversely of the frame, and are disposed in spaced parallelism with one another.

These rollers are of such a number as to permit a relatively wide space between one of the end members 7 and the end roller 9 as shown in Figure 1. Disposed in spaced parallelism to the end roller 9 is a drive shaft 10, which drive shaft has one end journaled in one of the side members 6 as at 11 and the other end extending through a bearing in the opposite side member to terminate in a squared extremity 12. The shaft 10 is so

formed at this extremity, for engagement with the socketed portion 13 of a suitable winding key 14. The purpose of this will become apparent during the following description.

On the opposite end of the shaft there is fixed thereto, a sprocket 15 and it will be noted that the rollers 8 are provided with sprockets 16, and that a drive chain 17, of the usual construction is trained over the sprockets 15 and 16. A spring 19 is associated with the shaft 10 as at 20, one end of the spring being secured by means of a bracket 21 to the adjacent end 7 of the frame 5 as shown in Figure 1. The spring 19 is in the nature of a spring motor and is adapted to furnish the power means for the drive shaft 10. A supporting bracket 22 has one end secured to the end 7 as at 23, and the opposite end of the supporting bracket 22 has a bearing formed on its extremity, through which bearing extends the shaft 10 as designated at 24.

A substantially rectangular frame like housing 25 has one end wall thereof secured to the end 7 as at 26, and it will be noted that this housing 25 extends at right angles to the member 7, and is of such a length as to permit the drive shaft 10 to extend through the side walls thereof in a manner clearly illustrated. Within the housing 25 is a mechanism, similar to a conventional mechanism used in clocks, and comprising, as herein shown, a plurality of gears, a hair spring, and a balance wheel, all adapted to function in correlation with one another in a manner herein presently to be described. That portion of the drive shaft 10 extending through the housing 25 has a gear 26 fixed thereon, which gear 26 is adapted to mesh with a small gear 27 fixed to a shaft 28, the opposite ends of said shaft being journaled in the side walls of the housing 25. The shaft 28 has also thereon a gear 29 in mesh with a gear 30 fixed to a shaft 31, which shaft 31 has in turn a gear 32 in mesh with a gear 33 fixed to a rotatable shaft 34, disposed in operative relation with respect to the last mentioned shaft.

The mechanism further includes a pendent wheel 35, fixed to the shaft 34, and which pendent wheel 35 in turn cooperates with a

100

pendent 36 in a suitable manner. The pendent 36 is rockably mounted on a shaft 37 and the one end of the pendent is suitably engaged with a balance wheel 38 fixed to the 5 rotatable shaft 39. A hair spring 40 is operatively associated with the shaft 39 and has one end thereof fixed to the adjacent end wall of the housing 25 all in a manner clearly illustrated.

- 10 The function of this mechanism as just described is to regulate or cut down the speed at which the motor, or spring 19 unwinds, when operating the drive shaft 10, which shaft 10 in turn by means of the chain and sprocket 15 connection between the shaft and the rollers rotates the said rollers 8 to turn the eggs coming in contact with the rollers. It is yet to be mentioned that a ratchet 41 is secured to the shaft 10 as at 42, and that this ratchet is 20 adapted to engage with a dog 43 carried by the sprocket 15 so as to prevent reverse rotation of the shaft, when the shaft is being rotated so as to tension the spring 19 for operating the entire device.
- 25 A plurality of relatively small rollers 44 have their respective axles 45 suitably secured to one of the side members 6, and these rollers 44 are disposed in spaced relation, and so located as to rest upon the chain 17, for holding 30 the said chain in operative contact with the sprockets 15 and 16.

The invention also contemplates the provision of an egg positioning frame structure designated generally by the numeral 46, and 35 illustrated to advantage in Figure 3. The egg positioning frame structure 46 comprises a frame of substantially rectangular formation having the side walls 47—47 and the end walls 48—48. This part of the frame structure 46 just described is preferably formed of metal. Strips 49 also preferably formed of tin extend in spaced parallelism longitudinally of the frame, and have their respective ends fixed in the adjacent end members 48 of 45 the frame. Suitable lengths of wire 50 extend transversely of the frame and are arranged in spaced parallelism to each other. These wire strips 50 pass through the metal partition members 49, and cooperate there- 50 with to provide individual egg receiving spaces.

Preferably adjacent the corners of the egg positioning frame structure, the said structure is provided with upstanding hook members 51, which members are adapted to engage the respective side walls 6 of the frame 5 to hold the frame or grid 46 substantially stationary within the said frame 5 and it is to be noted that the shanks of the hook members 51 are of sufficient length to permit the frame or grid 46 to rest upon the rollers 8 as clearly shown in Figure 2. However, in order to permit any longitudinal movement of the structure 46 within the frame member, 65 which movement may be caused by the rota-

tion of the rollers 8, one end member 7 of the frame is provided with a longitudinally extending slot 52, which slot is adapted to receive the adjacent end member 48 of the egg receiving structure as best illustrated in Figure 2.

70 Thus it will be seen that when the structure is suitably positioned within the frame 5, and the eggs 53 as shown in Figure 2 in dotted lines, are each placed in their respective compartments formed in the positioning frame 46, and extending through the compartments so as to contact with the rollers 8, it will be seen that during the rotation of the rollers, which rotation is actuated from the spring motor 19 through the connecting means already described the eggs will be turned continuously, during the said unwinding operation of the spring. As is obvious the clock mechanism herein described will control the 80 unwinding of the spring 19 so as to impart a slow but constant turning movement to the eggs.

85 From the foregoing then it will be seen that I have provided a thoroughly reliable and efficient egg turning tray, which consists of but few parts, is simple in construction and operation, and will be otherwise thoroughly reliable and efficient in use.

90 Even though I have herein shown and described certain detail structural elements and features of my invention, it is to be understood that the invention is susceptible of changes coming within the spirit of the invention as described, and the scope of the 95 appended claim.

Having thus described the invention, what I claim as new and desire to secure by Letters Patent is:—

100 An egg turning tray comprising in combination a frame, a plurality of relatively spaced transverse rollers journaled in the frame, means for simultaneously rotating all of said rollers in one direction, an egg positioning frame arranged in the first mentioned frame and resting on said rollers, and said first mentioned frame having an end member provided with a slot extending transversely of the frame in a plane above the rollers and through which an adjacent end of said positioning frame is projectable.

105 In testimony whereof I affix my signature.
ERNEST POCKRÄNDT.
